UNITED STATES PATENT OFFICE.

ELLA P. MAHLER, OF NEWARK, NEW JERSEY.

MATTING.

SPECIFICATION forming part of Letters Patent No. 746,722, dated December 15, 1903.

Application filed March 7, 1902. Serial No. 97,179. (No model.)

To all whom it may concern:

Be it known that I, ELLA P. MAHLER, a citizen of the United States, residing at Newark, in the county of Essex and State of New Jersey, have invented certain new and useful Improvements in Matting; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

The object of this invention is to secure greater durability, combined with efficiency of service, noiselessness when trod upon, and convenience in rolling up for removal preliminary to cleansing, and to obtain other advantages and results, some of which may be referred to hereinafter in connection with the description of the working parts.

The invention consists in the improved mat for doorways, floors, especially at the front of counters, bars, &c., and in the arrangements and combinations of parts of the same, all substantially as will be hereinafter set forth, and finally embraced in the clauses of the claim.

Referring to the accompanying drawings, in which like letters of reference indicate corresponding parts in each of the several figures, Figure 1 is a plan of my improved mat. Fig. 2 is a side view of the same, and Fig. 3 is a section taken at line x of Fig. 1.

In said drawings, a a indicate a series of block-like sections consisting, preferably, of cushions made of rubber or a composition containing rubber. These are preferably flat and oblong in plan and at their opposite ends are perforated to receive the means by which said sections are joined together. At the opposite sides of said blocks are arranged metallic plates b b, which are each perforated at or near their opposite ends, the perforations coinciding with the perforations in the block-like sections. Said plates serve not only to protect the block-like sections from wear at the edges, but as scrapers in removing the dirt adhering to the shoes and as links, providing tensile strength, so that when the mat is being rolled or when pulled from opposite ends the draft thereon will not be taken by

the cushions or blocks a lacking in tensile strength, but by said links. The blocks or sections a are arranged in series, the blocks 55 and their links or scraper-plates b of one series overlapping the blocks and links of the next series in order, the perforations of the two overlapping series of blocks and links coinciding, so that the bolt or connecting-rod 60 d may pass therethrough to bind or join the two said series, as indicated in Fig. 1. This arrangement of blocks, plates, and connections is repeated to secure the desired area or size of mat. At the opposite longitudinal 65 edges of the mat the same is provided with a series of border-plates d, so that no recesses of material depth are formed at said edges, and the opposite end edges of the mat are provided between the blocks or cushions a a 70 with short blocks or cushions a' a', which are perforated to receive the connecting-rods d and serve, with the blocks a, to give a smooth finish to the ends.

While ordinarily I prefer rubber or composition blocks, I can, to advantageously meet particular conditions, employ blocks of other material, such as wood, compressed fiber, burnt clay, &c.; but to secure the noiseless and cushion-like effect I desire ordinarily 80 greater elasticity, such as rubber affords.

After the connecting of the several series of block-like sections, link-plates, and rods the parts are held securely together by forming suitable heads e at the ends of said rods 85 either by using the nuts or by upsetting the rod metal in any suitable manner.

The sections a and plates b being pivotally arranged on the connecting-rods the said sections and plates permit of the mat being rolled 90 into a form convenient for transportation.

Having thus described the invention, what I claim as new is—

1. The improved mat comprising series of cushion-like blocks, rods, and metallic plates 95 distributed through the mat and extending from rod to rod to guard the said cushion-like blocks from tensile strain, substantially as set forth.

2. The improved mat comprising series of cushion-like blocks, rods connecting the same and pivotally holding the one series in connection with the next series and metallic plates pivotally arranged on said rods at va-

rious points between said blocks to take the tensile strain from said blocks, substantially as set forth.

3. The combination of the blocks *a*, scraper-
5 plates disposed on opposite sides of said blocks
a, and rods *d*, connecting said blocks and
scraper-plates, substantially as set forth.

4. The improved mat, comprising elastic
blocks, scraper-plates and connecting-rodsex-
10 tending through said blocks and scraper-
plates, substantially as set forth.

5. The improved mat, comprising flat elastic
blocks oblong in plan and perforated at
15 opposite ends, metal link-plates having per-
forations coinciding with those in the elastic
blocks, connecting- rods extending through
both the blocks and the metal link-plates and
series of border plates, all arranged and adapt-
ed to operate, substantially as set forth.

20 6. A floor - mat, consisting of blocks ar-
ranged in courses having openings alternate
with said blocks, said blocks having bores at
their ends and arranged with the bores in
alinement, rods passing through said bores,
25 riveting-plates connected endwise on the ends
of said rods and overlapping the entire side
edges of said mat, the ends of said rods be-
ing riveted against said riveting-plates, fill-
ing-pieces at the end edges of the mat ar-
30 ranged on the end rods, and auxiliary rods

passing through the filling-pieces and adja-
cent blocks, said auxiliary rods being riveted
at their ends on said riveting-plates, substan-
tially as set forth.

7. A floor-mat, consisting of a plurality of 35
sections joined rigidly together, said sections
composed of blocks arranged in courses hav-
ing openings alternately arranged with the
blocks, said blocks having bores at their ends
disposed in alinement, rods passing through 40
said bores of the blocks of the sections, inter-
mediate plates connected endwise each with
another on the ends of said rods and arranged
between the sections, riveting-plates connect-
ed endwise on the ends of said rods and over-
lapping the entire side edges of said mat, the 45
ends of said rods being riveted against said
riveting-plates, filling-pieces at the end edges
of the mat arranged on the end rods, and aux-
iliary rods passing through the filling-pieces 50
and adjacent blocks, said auxiliary rods be-
ing riveted at their ends on said riveting-
plates, substantially as set forth.

In testimony that I claim the foregoing I
have hereunto set my hand this 4th day of 55
March, 1902.

ELLA P. MAHLER.
